UNITED STATES PATENT OFFICE.

CHARLES H. DACON, OF ST. LOUIS, MISSOURI, ASSIGNOR OF ONE-HALF TO EDWARD F. BURGDORF, OF ST. LOUIS, MISSOURI.

CARBURETOR.

Application filed May 6, 1926. Serial No. 107,132.

My invention relates to carburetors and more particularly to carburetors such as are used to supply a combustible mixture of air and gasoline vapor to cylinders of integral 5 combustion engines.

Heretofore in carburetors of this type it has been found that all the gasoline is not vaporized and that, hence, the air passing through the carburetor is not combined only 10 with the vapor of the liquid fuel, but the air serves also as a carrying agent for minute particles of fuel. This so-called wet mixture is wasteful in that the particles of fuel are not broken up to a degree sufficient to obtain 15 the most power from the combustion which is incomplete, and, therefore, much of the energy which should be obtained is lost. Also, this mixture is harmful to the engine because when the wet mixture is injected into 20 the cylinders, some of the drops condense on the piston head, there to be carbonized, or fall on the cylinder walls to dilute the oil thereon.

The object of my invention is to provide a 25 carburetor which will cause a more complete vaporizing of the liquid fuel and will combine this vapor with the proper amount of air, thereby, producing a substantially dry gas which will be easily and completely 30 burned in the cylinders of the engine.

One form of a carburetor embodying my invention is fully shown in the accompanying drawings wherein similar letters are used to designate similar parts: Fig. 1 is a vertical section of the carburetor; Fig. 2 is a 35 horizontal section along the lines 2-2 in Fig. 1; Fig. 3 shows an elevation of the carburetor; and Fig. 4 shows a detail of construction hereinafter more fully explained.

Referring to the figures the carburetor has 40 a reservoir 1 for liquid fuel which enters into the reservoir through the main fuel inlet 2 and passes through the strainer screen 3 and through the passage 4 into the reservoir. 45 The needle valve 5 adapted to seat in the flared upper end 6 of the passage 4 and controlled by the movement of the float 7, governs the flow of fuel into the reservoir 1 and maintains a predetermined level of fuel 50 therein.

In the embodiment of my invention shown, 55 the needle valve 5 is slidably mounted so as to be capable of axial movement in the bridge 8 near the upper end thereof and in the bridge 9 in the lower end thereof. Secured

to the needle valve are the disks 10 which engage the fingers 11 of the crank arms 12. The crank arms 12, in turn, are journaled on the pins 13 on the valve housing 14, all as shown in detail in Fig. 1. When the fuel 60 in the reservoir 1 has reached a predetermined level the float 7 raises the balls 15 on the lower ends of the crank arms 12 thereby moving the fingers 11 downwardly and moving the needle valve 5 against the sides of 65 the flared upper end 6 of the passage 4 to shut off further flow of fuel into the reservoir. The housing 14 has the apertures 16 in the lower end thereof just above the upper end of the passage 4 so that fuel admitted 70 through said passage may flow into the reservoir 1. A removable plug 40 is, preferably, positioned at the bottom of the reservoir, as shown, whereby the reservoir may be drained 75 and the strainer screen 3 may be removed for cleaning.

The mixing chamber 17 has an air inlet 18 opening from the air tube 19. The inlet for the flow of air into the air tube 19 and, consequently, through the air inlet 18 of the mixing chamber may be regulated by the plate 20 which is adjustably mounted over the upper end of the air tube 19. A fuel inlet nozzle 21 is mounted in the mixing chamber and has the 80 preferably adjustable fuel inlet 22 through which fuel is sprayed into the mixing chamber. The inlet 22 is adjusted and, in turn, the flow of fuel therethrough is regulated by the needle 23 which has an enlarged lower end 90 threaded in the boss 24 and is provided with the pin 25 for turning. Fuel is supplied to the fuel inlet nozzle by means of the fuel duct 27 leading from the reservoir 1. The mixing chamber 17, preferably, has a venturi 95 26 positioned a short distance above the inlet opening of the nozzle 21.

The well 28 is, preferably, supplied with fuel from the reservoir 1 by means of the fuel duct 29 and, therefore, the normal level 100 of fuel in the well 28 will be the same as the predetermined level of fuel maintained in the reservoir. The well 28 may be provided with a drain plug 30.

A passageway 31 opens from the mixing 105 chamber 17 at a point above the normal level of fuel in the well 28 and opens into the well 28 below the normal level of fuel therein. An auxiliary air inlet pipe 32 discharges into the passageway 31 through the 110

air inlet 33, preferably, positioned below the normal level of fuel in the well 28. The auxiliary air inlet pipe 32, as shown in this embodiment, extends upwardly from the place of discharge into the passageway 31 to a point above the normal level of fuel in the well 28, and has at its upper end the suction operated valve 34 covered by a screen 35 which normally prevents dust or 10 foreign matter from passing into the auxiliary air inlet, all for the purpose more fully hereinafter set forth.

On the wall of the well 28 and adjacent 15 the opening from the passageway 31 into the well 28 is formed an arcuate shaped lip 36. A splash plate 37 extending inwardly from the walls of the well 28 and, preferably inclining downwardly, as shown in Fig. 1, is provided above the normal level of fuel 20 in the well, and also, a separating screen 38 is positioned in the outlet of the carburetor above the splash plate 37, but below the butterfly valve 39.

The normal level of fuel in the well 28 25 will be, as stated above, the same as the level in the reservoir 1 and, since, the passageway 31 opens into the well the liquid will normally back up into this passageway, as indicated in Fig. 1. However, when the 30 carburetor is operated as explained below the level of liquid in the well 28 will be raised somewhat and, since the average area of cross-section of the passageway 31 is comparatively small compared with the 35 average area of cross-section of the well 28, the liquid will be sucked out of the passageway 31 and, usually, the discharge opening 33 of the auxiliary air inlet 32 will be above the level of the liquid in the passage 31, 40 which level will be approximately even with the lower edge of the lip 36.

The operation of this form of my new and improved carburetor is as follows: When 45 the engine with which the carburetor is used, is cranked the suction created, as explained above, will change the normal level of liquid in the well 28 and will create a suction of air into and through the air tube 19 and through the air inlet 18 into the mixing 50 chamber 17. This air will then be drawn past the inlet 22 of the fuel inlet nozzle 21 in the mixing chamber and be mixed with the fuel sprayed from the fuel inlet nozzle 21, and this mixture of air and fuel will 55 pass into the passageway 31 and then downwardly through the passageway and under the lower end of the lip 36 and then will bubble upwardly through the liquid in the well 28. As the mixture bubbles upwardly 60 all of the sustained moisture in the mixture of air and liquid fuel formed in the mixing chamber will be retained by the liquid fuel in the well, and only a mixture of dry vapor and air will be released from the upper surface of fuel in the well 28. This mixture

will pass through the opening in the splash plate 37, through the separating screen 38 which will separate from the vapor any small particles of liquid fuel which may be drawn with it from the surface of the fuel 70 in the well, and will pass through the intake manifold of the engine into the cylinders to be burned therein. The mixture from the mixing chamber 17 will be diluted by air sucked into the passageway 31 through the auxiliary air inlet 33 of the air inlet pipe 32 when the suction is sufficient to overcome the tension of the spring 41 to allow the valve 34 at the upper end of the air inlet pipe 32 to be moved from its seat. I prefer that 80 the air from the auxiliary air inlet be discharged into the passageway just above the place of discharge of the duct 29 into said passageway so that the air before passing into the well 28 will take up some vapor of the fuel by passing over the fuel discharged from the duct 29. The flow of vapor and air through the outlet of the carburetor is controlled by the butterfly valve 39.

It may be readily seen that a device embodying my invention may be made in various forms or shapes and the parts may be placed in various arrangements without deviating from the spirit of my invention as embodied in the claims below.

What I claim as new and desire to secure by Letters Patent, is:

1. In a carburetor, the combination with a reservoir for liquid fuel, a well, a fuel duct for supplying fuel to said well from said reservoir, a mixing chamber, an air inlet, means for spraying fuel into said mixing chamber, a passageway opening from said mixing chamber at a point above the normal level of the fuel in said well and opening into said well below said normal level of fuel therein, and an auxiliary air inlet discharging into said passageway.

2. In a carburetor, the combination of a reservoir for liquid fuel, a well, a fuel duct for supplying fuel to said well from said reservoir, a mixing chamber having an adjustable fuel inlet and an air inlet, a passageway opening from said mixing chamber at a point above normal level of fuel in 105 said well and opening into said well below said normal level of fuel therein, and an auxiliary air inlet discharging into said passageway below said normal level of fuel in said well.

3. In a carburetor, the combination of a reservoir for liquid fuel, means for maintaining a predetermined level of fuel in said reservoir, a well, a fuel duct leading from said reservoir to said well, a mixing chamber having a fuel inlet nozzle discharging therein, means for supplying liquid fuel from said reservoir to said nozzle, said mixing chamber also having an air inlet, a passageway opening from said mixing chamber

- ber at a point above said normal level of fuel in said well and opening into said well below said normal level of fuel therein, and an auxiliary air inlet discharging into said 5 passageway.
4. In a carburetor, the combination of a reservoir for liquid fuel, a float operated valve for maintaining a predetermined level of fuel in said reservoir, a mixing chamber 10 having an air inlet, an adjustable fuel inlet nozzle discharging into said mixing chamber, a fuel duct for supplying fuel from said reservoir to said nozzle, a well, a fuel duct for supplying fuel from said reservoir to 15 said well, a passageway opening from said mixing chamber at a point above the normal level of fuel in said well and opening into said well below said normal level of fuel therein, and an auxiliary air inlet pipe dis- 20 charging into said passageway below said normal level of fuel in said well, said auxiliary air inlet pipe extending upwardly from the place of discharge into said passageway to a point above said normal level 25 of fuel in said well.
5. In a carburetor, the combination of a reservoir for liquid fuel, a mixing chamber having an adjustable fuel inlet and an air inlet, a well, a duct for supplying fuel from 30 said reservoir to said well, a passageway opening from said mixing chamber at a point above the normal level of fuel in said well and opening into said well below said
- normal level of fuel therein, and a splash plate extending inwardly from the wall of 35 said well above said normal level of fuel therein.
6. In a carburetor, the combination of a reservoir for liquid fuel, a float operated valve for maintaining a predetermined level 40 of fuel in said reservoir, a mixing chamber having an air inlet, a fuel inlet nozzle discharging into said mixing chamber, a fuel duct for supplying fuel from said reservoir to said nozzle, a well, a fuel duct for supply- 45 ing fuel from said reservoir to said well, a passageway opening from said mixing chamber at a point above the normal level of fuel in said well and opening into said well be- 50 low said normal level of fuel therein, an auxiliary air inlet discharging into said passageway below said normal level of fuel in said well, said auxiliary air inlet ex- 55 tends upwardly from the place of discharge into said passageway to a point above said normal level of fuel in said well, a suction operated valve arranged to regulate the flow of air through said auxiliary air inlet, a splash plate extending inwardly from the wall of said well above said normal level 60 of fuel therein, and a screen positioned above said splash plate in the outlet of said carburetor.

In witness whereof I have signed my name to this specification.

CHARLES H. DACON.
